UNITED STATES PATENT OFFICE.

HENRY E. HALSETH, OF AURORA, MINNESOTA.

BRACELET.

1,268,965.

Specification of Letters Patent. Patented June 11, 1918.

Application filed February 9, 1918. Serial No. 216,287.

To all whom it may concern:

Be it known that I, HENRY E. HALSETH, a citizen of the United States, residing at Aurora, in the county of St. Louis and State 5 of Minnesota, have invented certain new and useful Improvements in Bracelets, of which the following is a specification.

This invention relates to bracelets, and particularly to bracelets of that character 10 wherein a plurality of separable sections are employed, and is directed particularly to improvements in means for connecting the ends of the said sections.

The primary object of the invention is to 15 provide a bracelet of the character stated which has its sections connected in such manner as to permit of the same being readily moved toward or away from each other to allow the bracelet to be readily applied to or 20 removed from the hand, and which is equipped with improved means for normally holding the said sections in closed position and for maintaining the same so related.

A still further object of the invention is 25 to provide a device of the character mentioned which shall be of extremely simple and inexpensive construction, which has its operative parts so connected and arranged as to minimize the opportunity for wear or 30 breakage, which may be readily operated when desired, which will prove durable in use, and which will operate efficiently in practice.

With these objects in view, together with 35 others which will appear as the description proceeds, the invention resides in the novel formation, combination, and arrangement of parts, all as will be described more fully hereinafter, illustrated in the drawings, and 40 particularly pointed out in the claims.

In the drawings:—

Figure 1 is a sectional view taken through a bracelet constructed in accordance with the invention, the view illustrating the separable 45 sections in closed position,

Fig. 2 is an edge view of the bracelet, parts broken away, the sections of the bracelet being illustrated as they will appear when separated, and

50 Fig. 3 is a view similar to Fig. 1 and illustrating a slightly modified form of the invention.

Referring now more particularly to the drawings, 4 and 5 are the arcuate sections of

the tubular bracelet, the said sections being 55 positioned in the manner shown in the drawings so that their ends are normally engaged with each other.

The section 4 has secured in each end a retaining strip 6, the latter being formed preferably of spring metal and being of narrow width, and this strip is bent upon itself as shown and has the ends of the arms formed by so bending secured to the inner surface of the tubular member 4. The ends of the 60 said arm portions of the retaining strip may be soldered or in any other preferred manner secured to the tubular section, and it will be observed that the bight portion of each of the said strips protrudes slightly beyond 70 the ends of the section. The section 5 is similarly equipped with retaining strips, the latter being indicated at 7, and it will be observed that the retaining strips 7 are positioned in the hollow section 5 inwardly from 75 the ends thereof. The manner of applying these strips to the section 5 may be similar to that mentioned in connection with the section 4.

The adjacent ends of the sections 4 and 5 80 are connected by elongated links 8. These links extend within the adjacent ends of the said sections and inclose the retaining strips 6—7, so that the ends of the links will engage the said retaining strips when the sections are separated to limit the outward movement of the said sections. The links are preferably of such length as to permit of the bracelet being expanded an appreciable distance, thus permitting of the bracelet 90 being applied easily to hands or wrists of various sizes.

To maintain the sections with their ends normally engaged, each of the said sections is provided with a contractile member indicated generally at 9. In Figs. 1 and 2 of the drawings, this contractile member is in the form of an elastic band, the ends of which are engaged with the ends of the links 8 at the ends of the section, and the tendency of 95 these members is to move the sections toward each other.

In Fig. 3 of the drawings a slightly modified form of the invention is shown, and wherein the elastic bands referred to in connection with the description of Figs. 1 and 2 for forcing the sections together are dispensed with, contractile springs 10 being

used in their stead. These contractile springs are connected to the ends of the links 8 in any approved manner, the action of the said springs being similar to that of the bands or elastic straps above referred to.

As the ends of the sectional members 4 and 5 approach each other, the protruding bight portions 6 of the retaining strips carried by the section 4 enter the adjacent ends 10 of the section 5, and engage the inner walls of the said section with sufficient friction to hold the said sections firmly together. It is necessary only, however, to exert a slight degree of outward pressure upon the said 15 sections to cause the same to part when it is desired to expand the bracelet.

From the foregoing it is obvious that I have provided a bracelet which is of extremely simple construction and which will 20 operate efficiently to carry out the end for which it is used. The various parts of the device are so constructed and assembled as to preclude the possibility for accidental derangement or breakage.

While the present is a disclosure of what is believed to be the preferred embodiment of the invention, it is to be understood that the invention is not limited thereto, as various changes in the minor details of construction, proportion, and arrangement of parts may be resorted to if desired without departing from the spirit of the invention as 30 defined by the appended claims.

I claim:—

1. In a bracelet, the combination with a 35 pair of hollow arcuate members, retaining strips extending diametrically across the said arcuate members at each end thereof, links connecting the ends of said arcuate members and being engaged with said strips, 40 and a contractile member in each of said arcuate members connected at its opposite ends directly with the links in the said ends.

2. In a bracelet, a pair of hollow arcuate members open at their ends, retaining strips 45 in the ends of said members and extending diametrically across the same, the said strips being bent and having their extremities secured to the inner surfaces of their respective hollow members and extending inwardly from the open ends of the latter, the retaining strips in the ends of one of said arcuate members projecting therefrom and being adapted to fit within and engage the 50 walls of the adjacent ends of the opposite member, links engaged at their ends behind the strips in the ends of said arcuate members, and a contractile member in each arcuate member engaged at its extremities with the ends of the links at its open ends. 55

In testimony whereof I affix my signature in presence of two witnesses.

HENRY E. HALSETH.

Witnesses:

JOHN ABBANAT,
P. M. JOHNSON.
